UNITED STATES PATENT OFFICE.

WILLIAM K. EDGAR, OF COLORADO SPRINGS, COLORADO.

SEAL-LOCK.

SPECIFICATION forming part of Letters Patent No. 584,544, dated June 15, 1897.

Application filed February 24, 1897. Serial No. 624,794. (No model.)

To all whom it may concern:

Be it known that I, WILLIAM K. EDGAR, a citizen of the United States, residing at Colorado Springs, in the county of El Paso and 5 State of Colorado, have invented a new and useful Seal-Lock, of which the following is a specification.

The invention relates to seal-locks adapted particularly for use in securing freight and 10 other car doors; and it has for its object to provide a lock capable of use in connection with either a side or an end door, the same having common means for locking the staple-bolt and seal, and said means being adapted 15 when the seal has been removed to be disengaged with facility from the bolt and without the use of tools, and, furthermore, to simplify, strengthen, and otherwise improve the construction set forth in Patents Nos. 535,026 and 20 563,916, granted to myself and W. L. Sebring on March 5, 1895, and July 14, 1896, respectively.

Further objects and advantages of this invention will appear in the following description, and the novel features thereof will be particularly pointed out in the appended claims.

In the drawings, Figure 1 is a perspective view of a lock constructed in accordance with this invention applied in an operative position to a car-door, a portion only of the latter being shown, the locking-bolt being illustrated as in engagement with a staple. Fig. 2 is a vertical central section of the same, showing the parts in their locked position. 35 Fig. 3 is a similar view showing the parts in their unlocked position. Fig. 4 is a transverse sectional view taken in the plane of the locking-pin. Fig. 5 is a detail view of the locking-bolt detached. Fig. 6 is a similar 40 view of the locking-pin detached. Fig. 7 is a similar view of the trip or releasing pin detached.

Similar numerals of reference indicate corresponding parts in all the figures of the drawings.

1 designates a hasp adapted to be attached in the ordinary or any preferred manner to a door, and 2 a staple adapted to be secured to the jamb or casing of the door for engagement by the eye 3 of the hasp, said parts being of the ordinary construction.

4 represents the casing of the lock, which

is adapted to be secured to the framework of a car by means of bolts 5 or their equivalents, and formed longitudinally in this casing is 55 a bolt guide or way consisting of vertically-alined notches 6, formed in the upper and lower walls of the casing for the reception of the locking-bolt 7, which is adapted when extended to engage the staple to hold the eye of 60 the hasp in place thereon.

The casing is preferably made hollow to secure lightness, and the main or body portion thereof, in which the bolt is mounted, is fitted with a removable cap 8, in which is formed a 65 seal-seat, said cap being provided with lugs 9, which fit into the interior of the main or hollow portion of the casing and being secured to said main or hollow portion by screws 10 or their equivalents.

The seal-seat consists of parallel side shoulders 11, between which is a cavity 12 to form a space in rear of the seal 13 to facilitate breaking the latter, and these shoulders are connected at their lower ends by a transverse 75 ledge 14 in the same plane therewith. The seat is partly closed at its outer side to prevent the introduction or removal of the seal, except by sliding the same longitudinally and upwardly thereinto by means of overhanging 80 upper and lateral flanges 15 and 16, the lateral flanges 16 terminating short of the lower ends of the shoulders 11 to facilitate the engagement of the upper end of a seal with the seat.

The floor of the cavity in the seat is provided with a guide-opening 17 to register with a corresponding opening 18 in the rear wall of the casing for the reception of a locking-pin 18, which is adapted for operation in a 90 plane transverse to that of the locking-bolt 7, said locking-pin being provided near its front end with a reduced or neck portion 19, which when arranged in the plane of the locking-bolt is adapted to release the latter for 95 longitudinal movement. The bolt is slotted longitudinally, as shown at 20, and the main portion of this slot, while of a width sufficient to embrace the reduced or neck portion of the locking-pin, is insufficient in width to receive 100 the locking-pin at any other points than at said neck; but at the upper end of the slot in the bolt is an enlargement 21 of sufficient width to receive the body portion of the lock-

ing-pin. This enlargement, which necessarily forms an offset from the line of the slot, provides a shoulder 22, and when the body portion of the locking-pin is in engagement with this shoulder, as shown in Fig. 2, the locking-bolt is held from longitudinal movement.

In connection with the above-described mechanism I preferably employ a seal of frangible construction, the same being of clay or equivalent material, inscribed by number or otherwise to indicate destination or convey any other information which may be necessary, and this seal is provided at an intermediate point with an opening 23, through which is adapted to project the extremity of the locking-pin, whereby the seal is held from longitudinal movement in its seat. In other words, the locking-pin when extended, as shown in Fig. 2, serves not only to lock the bolt, but to secure the seal in its seat, the seal-seat being parallel with the bolt-guide.

Attached to and projecting laterally from the locking-pin is an operating-pin or finger-hold 24, which projects through a horizontal forwardly and rearwardly extending slot 25 in the side wall of the casing and carries a disk 26, whereby the slot is covered to prevent tampering with the interior of the lock and also to prevent the entrance of dirt. The cap of the casing is preferably provided with an ear 27, which fits in and partly closes the slot, as will be seen by reference to Fig. 4.

Formed on the rear end of the locking-pin is a stepped or shouldered ratchet 28, of which the shoulders are adapted to be engaged by the free end of a spring-actuated pawl 29, mounted in a rearward hollow extension 30 of the casing, the construction of said ratchet being such that the locking-pin may be advanced or drawn forwardly to engage the locking-pin or seal without manipulating the pawl, but cannot be moved in the opposite direction, except after previously tripping said pawl or disengaging the same from the ratchet.

In order to provide for tripping the pawl from the front of the lock, I employ a trip or releasing pin consisting of a stem 31, mounted in a guide consisting of registering openings 32 and 33, respectively, in the front and rear walls of the casing below the plane of the locking-pin and a lateral arm 34 at the rear end of said stem, said arm being provided with a beveled extremity to bear against the side surface of the pawl and move the latter in opposition to its actuating-spring when the stem is drawn forwardly. The front end of the stem is normally arranged in the seal-seat or in the cavity which is formed between the side shoulders of said seat, and attached to this projecting extremity of the stem is a finger-ring 35 of such a size that when the trip or releasing pin is pushed rearwardly to dispose its extremity in rear of the plane of the side shoulders of the seat said ring may lie in the cavity of the seat around the lock-

ing-pin. Hence when the parts are disposed as described the seal may be arranged in its seat to cover the extremity of the trip or releasing pin and the ring thereof and is secured in place by means of the locking-pin, as hereinbefore set forth. When it is desired to release the locking-bolt, the seal must be broken and the trip or releasing pin drawn forwardly to retract the pawl, whereupon the locking-pin may be moved rearwardly by pressure upon the finger-hold at the side of the casing to bring the reduced portion or neck of the locking-pin into the plane of the bolt and hence into alignment with the reduced portion of the slot in the bolt.

From the above description it will be seen that the only spring used in the construction of the lock is that which is employed in connection with the pawl and which is subject to no strain, except during the repression of the pawl to release the locking-pin. Furthermore, it will be seen that by forming the seal with a central opening through which the extremity of the locking-pin is exposed the frangibility of the seal is increased, while by being opaque and the opening therein being smaller in diameter than the ring which is attached to the front end of the trip or releasing pin the releasing devices of the lock are invisible.

Various changes in the form, proportion, and the minor details of construction may be resorted to without departing from the spirit or sacrificing any of the advantages of this invention.

Having described my invention, what I claim is—

1. In a seal-lock, the combination with a casing provided with a bolt-guide and a seal-seat, of a slotted bolt, the slot thereof having a terminal enlargement, a locking-pin mounted for movement in a guide arranged in a plane transverse to the bolt and extending through the enlargement of the slot therein, said locking-pin having a reduced portion or neck adapted to be received by the reduced portion of the slot in the bolt to allow longitudinal movement of the latter, and means for securing the locking-pin with its body portion in engagement with the enlargement of the slot in the bolt, substantially as specified.

2. In a seal-lock, the combination with a casing having a bolt-guide and a parallel seal-seat, of a slotted bolt fitted in said guide, the slot therein having a terminal enlargement, a locking-pin mounted in a guide disposed transversely with relation to the bolt-guide and extending through the enlargement of the slot in the bolt, said pin having a reduced portion or neck adapted to be received by the reduced portion of the slot in the bolt, a seal fitted in said seat and having an opening adapted to receive the front end of the locking-pin, and means for securing the locking-pin in its normal position, substantially as specified.

3. In a seal-lock, the combination with a

locking-bolt and seal having an opening, of a locking-pin mounted for movement transversely to the bolt and adapted when extended to engage said bolt and seal, the locking-pin 5 being provided with a ratchet, a pawl yieldingly held in operative relation with the ratchet of the locking-pin to secure the latter in its advanced position, and a trip or releasing pin, having a beveled face arranged in operative relation with the pawl, and a stem disposed contiguous to and adapted to be concealed by the seal, substantially as specified. 10 4. In a seal-lock, the combination with a casing having a bolt-guide and a parallel seal seat, the latter being cut away to form a cavity, a seal fitted in said seat to cover the cavity, and a bolt mounted in the bolt-guide, of a locking-pin mounted in a guide disposed transversely with relation to the bolt-guide 15 and adapted when extended or advanced to engage the bolt and seal, said pin extending through the cavity of the seal-seat, means for locking the pin in its advanced position, and a trip or releasing pin, arranged in operative 20 relation with the locking devices of the pin, and having a stem projecting terminally into 25

said cavity of the seat, and provided with a ring, adapted to be arranged in the cavity around the locking-pin when the seal is secured by the latter, substantially as specified. 30

5. In a seal-lock, the combination with a casing having a bolt-guide and seal-seat, a bolt mounted in said guide, and a seal fitted in the seat, of a locking-pin mounted for movement transversely with relation to the bolt 35 and adapted when in its extended or advanced position to engage both bolt and seal, an operating-pin projecting laterally from the locking-pin and extending through a slot in the side of the casing, whereby it is terminally 40 accessible from the exterior of the casing, means for locking the pin in its advanced position, and trip devices including a stem terminally concealed by the seal, substantially as specified. 45

In testimony that I claim the foregoing as my own I have hereto affixed my signature in the presence of two witnesses.

WILLIAM K. EDGAR.
